RADIO CLOCK

Application filed March 5, 1928. Serial No. 259,095.

The present invention relates to time-setting devices for electric circuit making and breaking mechanism, and has particular reference to devices of this nature especially adapted for controlling the circuits of radio receiving apparatus, with a view to automatically making and breaking circuits at predetermined intervals.

Accordingly, the primary object of my invention is to devise a mechanism adapted to be associated with a clock and in connection with an electric circuit and adapted to be manually regulated and set for making and breaking the circuit by the operation of the clockwork at any desired times for which said mechanism is set.

It is also sought to provide a device of this general character which will be adapted to control the circuit by manually adjusted means independently of the usual control switch provided in the circuit.

It is further sought to provide a time controlled mechanism of this nature which will not be limited to radio receiver work, but which will be adapted for general use in the control of circuits where the automatic making and breaking of the circuit at predetermined time intervals is required.

With these general objects in view, the invention will now be described by reference to the accompanying drawings illustrating one form of construction and arrangement for embodying the same in practical form, after which those features and combinations deemed to be novel will be set forth and claimed.

In the drawings—

Figure 1 is a front elevation showing a portion of the front panel of a radio receiving cabinet, equipped with the present improvements;

Figure 2 is a rear elevation of the same;

Figure 3 is a plan view of the same on a larger scale and with the panel portion of the cabinet in horizontal section;

Figure 4 is a similar plan view with the clock casing broken away to disclose the parts within;

Figure 5 is an elevation, with parts broken away and showing the rear side of the setting mechanism hereinafter referred to;

Figure 6 is an edge view of the same;

Figure 7 is a sectional view, representing a section taken on the line VII—VII of Figure 5;

Figure 8 is a detail section of the diaphragm and insulating elements hereinafter referred to, and represents a section taken on the line VIII—VIII of Figure 5;

Figure 9 is an enlarged face view of the front side of the clock mechanism with the circuit connections thereto;

Figure 10 is an enlarged fragmentary detail view showing a portion of the rotating insulating element and connection to its driving or adjusting gear; and

Figure 11 is an enlarged sectional detail illustrating the drive relation between the clockwork shafts parts connected therewith.

Referring now to the drawings in detail, these illustrate the invention in its operative relation to a radio receiving cabinet 20 provided with the usual exterior knob 21 for operating a switch device 22 for opening and closing the circuit through the receiver, said circuit including the conductors 23 connected with the binding posts 24 of the switch 22. Connected with these same posts 24, or the conductors 23, are a pair of secondary leads 25, or conductors 25, leading to the radio or circuit-controlling clock device comprising a clock casing 26 containing any suitable clock mechanism and including also a suitable auxiliary casing 28 with its dial plate or face 29 set in an opening in the front panel of the cabinet 20 and to which the flange or margin 30 of said auxiliary casing is secured by screws 31 or the like, as represented in Figures 1 and 2. Suitable winding mechanism

may also be provided for the clockwork including an exterior knob 32 on the panel front, and gearing 33 connected with the winding shaft 41 of the clock (Figure 2).

5 The time or program setting mechanism comprising my invention is housed within the auxiliary casing 28 between the dial plate 29 and one of the outer frame plates 34 of the clockwork, the edge of the plate 29 being 10 provided with spacing fingers 35 terminating in attaching lugs 36 adapted to be inserted through openings 37 of the plate 34 for rigidly securing together said plates 29 and 34, and with the central opening 38 of the 15 dial face in line with the shaft 39 of the minute hand 40 of the clock mechanism. In the present construction this shaft 39 as well as the sleeve shaft 42 of the hour hand 44 are made sufficiently long to span the extra 20 distance between the plate 34 and the face of the dial.

25 Journaled upon the sleeve shaft 42 is a gear ring 45, the interior portion of which comprises a helical diaphragm 46 of suitable conductive material, formed with a lug 47 for keying the ring and diaphragm to a sleeve 48, which is also lined with an insulating sleeve 49 fitting the shaft 42.

30 Meshing with the gear ring 45 is a pinion 50 of fibrous material for insulating purposes, and this pinion in turn meshes with a second pinion 51 fast to a short shaft 52 journaled in an extension 53 from a plate 54 which fits against the rear face of the 35 dial plate 29. One end of the shaft 52 projects out through the margin 30 of the casing 28, where it is fitted with a knob 55.

40 Intermeshing with the helical conducting diaphragm 46 is a similar helical-shaped non-conducting or insulating element 60 having a central hub portion 61 fitting over the sleeve 48 and keyed, as indicated at 62 (Figure 10) to the central opening 63 of a gear wheel 64 which rotates about said hub 61 45 as an axis. The teeth of the gear wheel 64 mesh with a pinion 66 which in turn meshes with a pinion 67 on a short shaft 68 journaled in another extension 70 from the plate 54 and projecting out through the margin 30 50 of the casing 28, where it also is provided with a knob 72 for turning purposes. The pinions 50 and 66 are journaled on pins 73 carried by the plate 54. A sheet 75 of suitable insulating material is interposed between the gear ring 45 and wheel 64 and formed with a central opening 76 for the hub 61 and with a smaller opening 77 for one of the pins 73 to help retain said sheet 75 in position. The other pin 73 carries a fiber latch plate 78 retained by a nut 80 in position for overlapping the edge of the gear ring 45 and assisting in keeping the latter in proper position and entirely insulated from the remaining parts.

60 65 From this construction it will be seen that

by the turning of the gear ring 45 and wheel 64 and correspondingly rotating the diaphragm 46 and insulating element 60, these latter may be moved into greater or less intermeshing relation for exposing a greater or less area of the diaphragm 46 into contacting relation to a yielding revolving brush element 82 which is carried by the sleeve shaft 42 but insulated therefrom by a flanged fiber bushing 84. The resilient character of the brush 82 maintains contact with the diaphragm or element 60 regardless of the slight movement of these parts axially of the shaft 42 due to the different intermeshed relations of said parts as they rotate.

70 75 The base of the brush element 82 is provided with a groove 86 for contact with the forked portion 87 of another brush element 88 connecting with a contact screw 90 secured to the frame plate 34 and insulated therefrom by a suitable insulating washer 92; to this contact screw is also secured one of the conducting wires 25. The other conducting wire 25 is connected to a contact screw 94 insulated by a washer 96 from the frame plate 80 34, and to this screw is also secured one end of a second resilient brush 97 (see Figures 4 and 9) the free end of which extends in position for maintaining yielding contact engagement with the margin of the gear ring 45.

90 95 From the foregoing it will be understood that the gear member 45 and its diaphragm element 46 are completely insulated from the remaining parts, and the circuit can be closed through the conducting wires 25 only when both of the brush elements 82 and 97 are in electric contact with said gear member and diaphragm element, which is possible for only such periods as the brush element 82 is contacting with a portion of the diaphragm 100 element that has been uncovered by the insulating element 60. The length of such period of course corresponds to the extent of such uncovered area of the diaphragm element and the time required for the brush 105 82, which moves at the rate of the hour hand, to traverse this area. By operating the knobs 55 and 72, it is apparent that the gear members 45 and 64 may be conveniently turned for bringing the elements 46 and 60 into 110 more or less completely intermeshed relation, and thus varying the extent of travel, and hence the length of the corresponding time period during which the brush is in contact with the diaphragm and thereby the 115 length of time the circuit will be closed through the receiving set.

120 125 The lug 47 projecting out from the diaphragm element 46 limits the relative rotative movement of the parts 46 and 60 in one direction, and a lug 98 on the outer margin of the element 60 similarly limits said rotative movement in the opposite direction by engaging one of the edges of the element 46; and by providing notches 99 and 100 in 130

the elements 46 and 60, respectively, for sufficiently clearing said lugs 98 and 47, respectively, to permit either complete uncovering or complete covering of the diaphragm element 46, it is apparent that the circuit may be maintained either continuously closed or continuously open as the case may be. Obviously, also, this operation is entirely independent of the operation of the switch element 22.

A pair of indicator hands 101 and 102 are attached to the outer ends of the hub 61 and sleeve 48, respectively, and preferably finished in contrasting colors, e. g. 15 green and red, respectively. These indicator hands are so attached as to cause the green hand 101 to aline radially with the edge of the insulating element 60 which is exposed in Figure 5, and the red hand 102 to be 20 radially alined with the edge of the diaphragm element 46 which is also exposed in said view, and since the rotating brush element 82 is similarly alined in the same radial relation with the hour hand 44, it will be 25 evident that the green and red hands 101 and 102 will register the beginning and end of the exposed area of the diaphragm element, and hence the points on the dial 29 at which the hour hand will be located at the beginning 30 and end of the corresponding time interval. It is therefore only necessary to set the colored hands at those points on the dial corresponding to the positions of the hour hand at the beginning and end of any given 35 period of time, as, e. g. the time interval corresponding to a radio program which the operator may desire to receive, and it will be evident that the receiving circuit will be automatically closed and opened at the beginning 40 and end of the program.

If desired, the clock dial may be calibrated to show, e. g. ten minute intervals besides the usual minute scale, for convenience in setting the hands 101 and 102, as represented in Figure 1 for one of the five minute spaces, and which of course may be carried out entirely around the face of the dial.

While the provision of the separate knobs and gear connections to the diaphragm element 46 and insulating element 60 affords independent adjusting means for varying the positions of these elements, it is possible to use but one of said knobs and gear connections, for example the knob 55, for carrying out the complete operation of setting the clock for a program; this may be done by turning the knob 55 in a counterclockwise direction for positioning the hand 101 at the proper point (corresponding to the beginning 50 of the program), in which operation both hands will move in unison, the lug 47 being seated in the notch 100 and the diaphragm element 60 therefore carrying the insulating element along with it in the same 55 direction; then by turning the knob in the

opposite direction the diaphragm element 46 and the other hand 102 will be turned forward to the proper point corresponding to the end of the program, there being sufficient friction for holding the insulating element and its operating connections stationary during this setting of the hand 102. On the other hand, the setting operation may be carried out entirely by operation of the knob 72, first in a clockwise direction for positioning the hand 102 at the proper point corresponding to the end of the program, both hands moving in unison as before and the insulating element 60 carrying the diaphragm element along with it in the same direction; then by turning said knob 72 in the opposite direction, the insulating element will be turned backward to the proper point corresponding to the beginning of the program while friction operates to hold the diaphragm element stationary during this setting of the hand 101. Thereafter, in case it should be desired to continue the program beyond the time set, the said knob 55 can be turned to carry the hand 101 further around the dial which will extend the exposed area of the diaphragm and result in keeping the receiver circuit closed for a correspondingly longer time. Similarly, the right hand knob 72 may be rotated for moving the insulating element backwards for closing the circuit earlier and thereby starting the program sooner if desired, without affecting the time already set for the stopping of the receiver's operation by the other knob 55.

It will thus be apparent that I have devised a practical and efficient, and yet comparatively simple, arrangement and construction for carrying out the desired objects of the invention, and while I have illustrated one practical embodiment thereof, it is obvious that the invention is not to be restricted to this specific form and that it is susceptible of other forms of embodiment for carrying out the time regulation and control of the circuit making and breaking function of many types of electric apparatus. I therefore desire to be understood as reserving the right to make all such changes and modifications as may fairly fall within the scope of the appended claims.

Having thus described my invention what I claim and desire to secure by Letters Patent is:

1. In a time controlled circuit breaking device, the combination of a circuit making and breaking device including a pair of cooperative and relatively movable elements adapted to expose varying amounts of conductive material, a brush traversing said elements, a clock provided with connections for actuating said brush, separate means for selectively positioning said elements for different time intervals, and indicators on the

- face of the clock and actuated by said positioning means for registering the respective starting and stopping points of the corresponding time interval.
5. 2. In a time controlled circuit breaking device, the combination of a circuit making and breaking device including a pair of cooperative and relatively movable elements adapted to expose varying amounts of conductive material, gear mechanism operative to move said elements in unison in one direction for setting one of said elements and thereafter operative to independently move the other element in the opposite direction to position said other element in accordance with the length of a given time interval, and a clock-actuated brush traversing said elements.
10. 3. In a time controlled circuit breaking device, the combination of a circuit making and breaking device including a pair of cooperative and relatively movable elements adapted to expose varying amounts of conductive material, a gear mechanism operative to move both of said elements in unison in one direction for setting one of said elements and thereafter operative to independently move the other element in the opposite direction to position said other element in accordance with the length of a given time interval, a separate gear mechanism for imparting an independent adjusting movement to said other element, and a clock-actuated brush traversing said elements.
15. 4. In a time controlled circuit breaking device, the combination of a circuit making and breaking device including a pair of cooperative and relatively movable elements adapted to expose varying amounts of conductive material, a brush traversing said element, a clock provided with connections for actuating said brush, gear mechanism operative to move said elements in unison in one direction for setting one of said elements and thereafter operative to independently move the other element in the opposite direction to position said other element in accordance with the length of a given time interval, and indicators on the face of the clock having connections with said elements for actuation thereby to respectively register the starting and stopping points of the corresponding time interval.
20. 5. In a time controlled circuit breaking device, the combination of a circuit making and breaking device including a pair of cooperative and relatively movable elements adapted to expose varying amounts of conductive material, said elements having inter-
- gagement for setting one of the elements and thereafter imparting an opposite independent movement to the other element for setting the latter in accordance with the length of a given time interval, and a clock-actuated brush traversing said elements.
